UNITED STATES PATENT OFFICE.

HOWARD D. CLAYTON, ORVILLE E. COOK, AND SANFORD L. CLUETT, OF TROY, NEW YORK, ASSIGNORS TO CLUETT, PEABODY & CO., INC., OF TROY, NEW YORK, A CORPORATION OF NEW YORK.

THERMOSTATIC TEMPERATURE CONTROLLER FOR FOLDING AND PRESSING MACHINES.

Application filed October 22, 1921. Serial No. 509,520.

To all whom it may concern:

Be it known that we, HOWARD D. CLAYTON and ORVILLE E. COOK and SANFORD L. CLUETT, citizens of the United States of America, and residents of Troy, in the county of Rensselaer and State of New York, have invented new and useful Improvements in Thermostatic Temperature Controllers for Folding and Pressing Machines, of which the following is a specification.

This invention concerns pressing and folding machines such for example as are employed in the commercial production of collars and cuffs, and relates more particularly to a method and means whereby the proper operative temperature of a presser element of such machine may be substantially maintained within the limits prescribed on the one hand by efficiency and rapidity of operation and on the other hand by the temperature at which substantial weakening of the material begins.

In the manufacture of collars and cuffs the margin of the blank is folded inwardly over the edge of a suitably shaped die plate and is then subjected to heat and pressure for a period of time sufficient to set the fold. Three factors then enter into the operation, to wit, the pressure to which the goods are subject for securing intimacy of contact thereof with the heated presser element, the period of time during which the goods are subjected to pressure, and the temperature of the heated element. The temperature factor may vary with the individual operator; and to enable him to obtain as large an output as possible in a given time the tendency is to maintain the temperature at as high a point as is permissible without substantial injury to the fabric. Ordinarily the only index by which the operator is able to determine such permissive temperature is the yellowing of the fabric due to actual scorching of the same and even with proper care on the part of the operator, such determination by color alone must be subject to great variation not only by reason of the idiosyncrasy of the individual operator but on account of changing light conditions and variations in the material operated upon.

Not only is the appearance of scorch an

unreliable criterion by which to gage the permissive upper limit of temperature, but it is undesirable for other reasons to attempt to employ this method of determining the temperature.

Results of extensive tests have proven that the strength of fabrics and particularly bleached fabrics such as are commonly employed in the manufacture of collars and cuffs is substantially unaffected by temperatures up to approximately 300° F., but that upon increase in temperature above such point the strength of the material decreases very rapidly, the decrease approximately from 20% to 50% at a temperature of about 400° F. at which yellowing or scorch first appears. It is thus clear that if the appearance of coloration of the material is to be relied upon in determining the permissive temperature, very positive damage to the material may result, even though the operator be using the utmost care and skill.

The object of the present invention accordingly is to provide a method and means whereby the temperature to which fabric is subjected during the pressing operation may be automatically prevented from rising to a point at which substantial damage to or loss of strength of the fabric would take place and maintained substantially uniform at the point most desirable for efficient operation, and to this end the invention may consist, in general, of providing a method of and means for maintaining the heat approximately at a predetermined degree, or within a predetermined range, below the scorching temperature, and preferably approximately at the temperature where the strength of the blanks begins to be affected, and for automatically regulating the heat irrespective of the rate of operation so that the machine does not overheat if operated slowly or if left idle with the heat turned on.

When employing an electric heating element it is also desirable though not necessary to provide a resistance (or reactance) in the heating circuit whereby rapid fluctuations in the temperature of the heating coil may be prevented. As thus arranged the resistance will ordinarily be shunted, but when the bed plate reaches the predetermined maximum temperature the heat-responsive regulator

will cut in the resistance, thus decreasing the current flow in the heating coil, the operation of the various parts thus serving to maintain the bed plate at a substantially uniform temperature.

While electrical means for heating the bed plate is most convenient, it is contemplated that thermostatic controlling may be employed in connection with other heating means, the thermostat in such cases serving to actuate suitable valves or other devices, either directly or indirectly, whereby to determine the temperature of the bed plate.

In accordance with this invention, with the heat-responsive regulator initially set to operate at a temperature below the scorch point and preferably slightly below that temperature at which substantial decrease in fabric strength begins, the operator may proceed without particular care, so far as danger from overheating of the machine is concerned, while it is substantially impossible for him to increase the temperature beyond the proper maximum if he be so disposed.

Uniformity and maximum strength in the product is thus assured while less skill on the part of the operator is necessary.

One arrangement exemplifying means whereby the invention may well be carried into effect is illustrated in the accompanying drawings, in which,—

Figure 1 is a diagram illustrating graphically the variations in tensile strength of a piece of textile fabric throughout progressive increase in temperature and also illustrating the progress of scorching of such fabric under rising temperatures;

Figure 2 is a plan view of a folding and pressing machine of known type and to which the present invention may be applied;

Figure 3 is a transverse cross section to smaller scale on a line such as *a*—*b* of Fig. 2;

Figure 4 is a fragmentary end elevation of the machine of Fig. 2, showing the die plate in elevated or inoperative position;

Figure 5 is a fragmentary side elevation, partly in longitudinal section and on a larger scale, of the bed plate of the machine;

Figure 6 is a transverse cross-section on the line *c*—*d*, of Fig. 5; and

Figure 7 is a diagrammatic representation of a system of electrical circuits which may be employed in carrying the present invention into effect.

Referring to Fig. 1, the diagram shown therein is constructed with ordinates representing tensile strength in pounds per linear inch of a test piece of fabric, while abscissæ indicate temperatures in degrees Fahrenheit. The line 1 upon this diagram shows the relation of tensile strength to temperature at any given point, the period of

subjection of the fabric to the temperatures employed in making the tests being in all cases approximately 30 seconds. In this diagram it will be noted that the initial tensile strength is approximately fifty-three pounds, indicated at 2, and that this strength remains substantially uniform as the temperature increases until a point approximating 300° is attained, this point being indicated at 3. As the temperature increases from this point, a very rapid decrease in tensile strength results until at the point 4 of the line 1, which corresponds to a temperature between 500° to 600°, charring of the material has occurred to such an extent as to reduce the tensile strength to almost nothing. In the upper part of this diagram is indicated the progressive change in color due to scorching of the fabric as the temperature is increased.

Referring to the diagram, it will be noticed that the color of the fabric remains substantially unchanged as the temperature is increased from 100° to 400° and that the first visible yellowing of the fabric occurs at approximately 400° from which point the intensity of the coloration continually increases up to the point of actual destruction of the fabric where it becomes almost black. Comparing the point 6 at which scorching begins to be visible, with the point 3 at which decrease in tensile strength commences, it will be evident that there is a substantial range of temperature, below that at which injury to the fabric is visible to the eye, through which such injury actually takes place, such range approximating 100° of temperature increase. In order to avoid substantial injury to the fabric in accordance with the present invention, the operative temperature is maintained at a point substantially below that at which scorching becomes visible, namely 400° in the example illustrated, although in the practical operation of folding machines of modern type where the period during which the fabric is subjected to the working temperature is often less than three seconds a somewhat higher upper limit of temperature is found to be permissible, such upper limit of working temperature in any case being approximately that at which decrease in tensile strength actually begins under working conditions.

Referring to Figs. 2 to 7 a pressing machine of ordinary form is illustrated, comprising a frame 7, carrying the table 8 provided with the bed plate 9, such bed plate constituting one of the presser elements and having a swinging arm 10 which serves to support the die plate 11 which forms the co-operating presser element. The machine is also provided with folder bars 12 and 13, respectively operable by means of eccentric pins such as 14 carried by suitably actuated

shafts and which bars may be guided in their movement upon the table 8 by means of brackets such as 15 and 16. Secured to the respective folder bars are folder blades 17, 18, respectively which cooperate with the edge of the die plate 11 in folding and pressing the material.

In accordance with the present invention, the bed plate is preferably made hollow, or 10 provided with suitable cavities and within the same is housed an electrical heating coil 19, preferably made in two parts as shown. This heating coil has terminals such as 20 to which are secured the ends of wires 21 15 and 22 respectively. Such wires may be connected to the terminals 23 and 24 of a suitable power circuit by means of a manually operable switch 25, whereby current may be caused to flow through the coil 19 20 for heating the bed plate. Interposed in the wire 22 may be a resistance coil 26, the term "resistance" being here employed to designate any suitable means whereby the maximum current flow (either direct or alternating 25 current) through the wire 22 may be determined. That portion of the circuit including the coil 26 may be shunted by means of a secondary circuit comprising the wires 27, 27^a, whose terminal portions are electrically connected by means of a circuit making switch 28. The switch 28 is actuated by means of a relay 29, such relay being included in a circuit comprising the wires 30 and 31 suitably supplied with current by 30 means of a battery 32 or in other desired manner. Such circuit may have a manually operable switch 33, if desired. The arrangement of the circuit breaker 28 and the relay 29 is such that when no current flows 35 through the relay, the shunt circuit including the wires 27 and 27^a is open.

A chamber is formed in the bed plate extending upwardly from the lower side thereof so as to leave a relatively thin partition 40 or wall between the chamber and the blank supporting surface of the plate. This chamber is preferably located between the two parts of the heating coil 19 although if desired this chamber may form the central 45 part of a large chamber in which the coils are arranged. Within this central chamber a box 34 is secured by means of screws 35 or in other desired manner. The bottom wall 36 of this box is provided with a pair 50 of insulated binding posts 37 and 38 to which the terminals of the wires 30 and 31 are secured. An insulating block 36^a is mounted upon member 36, and secured to the surface of such block is a thermostatic 55 element 39 lying closely adjacent to and substantially parallel with the upper surface of the chamber, such element being electrically connected to the binding post 38. The free extremity 40 of the member 39 overlies 60 the upper end of an adjustable contact mem-

ber 41, such member being threaded for engagement with a threaded opening in a metallic plate 42 which is electrically connected to the binding post 37. A lock nut 43 engages the lower end of the member 41 whereby such member may be retained in adjusted position. As the thermostatic element 39 is located within the bed plate, it is subject to the temperature thereof and thus partakes of any substantial variation in the temperature of the bed plate.

The contact member 41 is initially adjusted and fixed in such position that when the bed plate has attained the maximum desired temperature, that is, a temperature substantially below the scorching point of the fabric being operated upon and approximating the point at which the tensile strength of the fabric begins to decrease, the thermostatic element will be about to 80 break contact with the member 41. Until such point is reached however, current flows through the circuit comprising the wire 30, the post 37, contact member 41, the element 39, the post 38, the wire 31 and the relay 90 29. The relay is thus energized thereby causing the circuit making and breaking element 28 to close the circuit through the shunt comprising the wires 27, 27^a. The full current is thus permitted to flow 95 through the heating coil 19 whereby the bed plate is gradually raised in temperature until at the maximum desired temperature the member 40 leaves the member 41. This immediately breaks the circuit through the 100 relay, permitting the member 28 to open the shunt circuit and thus causing the heating current to flow through the resistance 26. This reduces the heating current to a substantial degree whereby the temperature of 105 the bed plate is gradually diminished. As the thermostatic element 39 may be made quite sensitive to temperature variations and as the threaded member 41 is capable of relatively minute adjustment, it is clear that 110 by the employment of the apparatus just described, the temperature of the bed plate may be maintained within very narrow limits or substantially constant and at the most desirable temperature for securing the desired result upon the fabric without any danger of injury thereto by excessive heating. As above stated the temperature is 115 preferably maintained approximately at the point where the strength of the fabric begins to be affected, that is, approximately at the point where the strength curve begins to decline (Fig. 1), this point depending upon the character and condition of the fabric, the length of time during which the heat is 120 applied to the fabric, etc.

Under some circumstances it may be desired to dispense with the resistance element 26, in which case such element may be entirely omitted, or a manually operable switch 130

44 may be employed for cutting out such coil when desired. In this case the opening of the circuit at the point 28 would cause entire cessation of current flow through the heating coil. However, the employment of the resistance 26 is preferred as conduced to greater uniformity in the heat supplied to the bed plate.

When other means is utilized for heating 10 the bed plate of a pressing and folding machine, such for example as steam or gas, it is evident that the thermostatic control herein disclosed may be utilized for controlling such heating means, it being merely 15 necessary to provide electrically actuated controlling valves suitably connected to the thermostat whereby to determine the amount of gas or steam admitted, and it is contemplated that such a change may be made 20 without departing from the spirit of the invention. It is also to be understood that the invention is not in any manner dependent upon the specific form of thermostatic device employed, or its precise location with 25 respect to the operative parts of the mechanism, but that various changes may be made therein such as may occur to those familiar with the art.

We claim:

30 1. A machine for folding collar and cuff blanks comprising a presser element, means for heating said element, and means associated with said element and responsive to fluctuations in the temperature thereof for controlling the heat supplied to the heating means, said heat responsive element being constructed and arranged to cut off the supply of heat when the temperature of the presser element reaches that point at which 35 the strength of the fabric of the blank begins to be affected.

40 2. A machine for folding collar and cuff blanks having a presser element and means for heating said element, and electrically energized means for controlling the amount of heat supplied to the heating means comprising a member responsive to fluctuations in temperature of the presser element and disposed within the latter, said controlling 45 means being constructed and arranged automatically to maintain the temperature of the presser element at approximately that point at which the strength of the fabric of the blank begins to be affected.

50 3. A machine for folding collar and cuff blanks having a presser element, means for heating said element, and controlling means for controlling the heat supplied to said element, said controlling means comprising a 55 member responsive to fluctuations in temperature of the presser element and being constructed and arranged automatically to maintain the temperature of the presser element between 300° and 400° F.

60 4. A machine for pressing collar and cuff

blanks comprising a presser element, heating means for said presser element, means normally operative to supply heat in predetermined amount to said heating means whereby to raise the temperature of the presser element approximately to 300° F., and means operative upon increase in temperature of the presser element to a determined point above 300° F. and below 400° F. for reducing the amount of heat supplied to the heating means.

5. A machine for pressing collar and cuff blanks comprising a bed plate, an electrical coil for heating the bed plate, an electrical circuit for supplying energy to the heating coil, a resistance in said circuit, means normally shunting said resistance whereby to supply electrical energy to the coil sufficient to raise the temperature of the bed plate approximately to 300° F., and means responsive to increase in temperature of the bed plate to a point approximating that at which the strength of the fabric of the blank begins to decrease, for automatically opening the shunt circuit whereby to render the resistance effective for cutting down the supply of energy to the heating coil.

6. A machine for folding collar and cuff blanks comprising a presser element, means for heating said element, and means disposed closely adjacent to the blank engaging surface of said element and responsive to fluctuations in the temperature thereof for controlling the heat supplied to the heating means.

7. A machine for folding collar and cuff blanks comprising a presser element having a cavity therein, heating means within the cavity, and a controlling member also housed within the presser element and subject to fluctuations in temperature thereof for determining the heat supplied to the heating means.

8. A machine for folding collar and cuff blanks comprising a presser element having a cavity therein, means for heating the presser element, a heat responsive member disposed within the cavity in the presser element, and means controlled by said heat responsive member for varying the amount of heat supplied to the heating means.

9. A machine for folding collar and cuff blanks comprising a presser element having a cavity therein, heating means disposed within the cavity, a heat responsive member associated with said presser element and subject to the temperature thereof, and means controlled by said heat responsive member for determining the heat supplied to the heating means.

10. A machine for folding collar and cuff blanks comprising a bed plate having a cavity therein, heating means within the cavity, a heat responsive element within the cavity, means for determining the heat sup-

plied to the heating means, and means actuated by said heat responsive element for controlling the heat determining means.

11. A machine for folding collar and cuff blanks comprising a bed plate having a recess in its under side, said recess extending nearly to the upper surface of the bed plate and being separated therefrom by a relatively thin wall, a heat responsive member disposed within the recess and adjacent to said wall so as to be subject substantially to the same temperature as the blank engaging surface of the bed plate, and heating means for the bed plate controlled by the heat responsive element.

12. A machine for folding collar and cuff blanks comprising a bed plate having a cavity therein, heating means for the bed plate, a box secured within the cavity, a heat responsive circuit breaker within the box, and an electrical circuit controlled thereby for determining the heat supplied to the heating means.

13. A machine for folding collar and cuff blanks comprising a presser element having a surface for engagement with the blanks to be folded, an electrical heating coil housed within a cavity in said element, a heat responsive member within a cavity in the element, and electrically actuated means controlled by said heat responsive element for determining the current flowing through said heating coil.

14. A machine for folding collar and cuff blanks comprising a bed plate having a cavity therein, heating means within said cavity, a box secured within a cavity in the bed plate, said box having an adjustable contact point therein, a heat responsive member arranged within the box and constructed and arranged to contact with or move away from said contact point under changes in temperature in the bed plate, and an electrical circuit having its terminals connected to the contact point and heat responsive member respectively and operative in accordance with the movements of said heat responsive member to determine the heat supplied to the heating means.

15. A machine for pressing collar and cuff blanks comprising a presser element, an electrical coil for heating said element, means for supplying a predetermined amount of electrical energy to said coil, and means operative upon increase in temperature of the presser element substantially above 300° F. for reducing the amount of energy supplied to the heating coil.

16. A machine for folding collar and cuff blanks comprising a presser element, an electrical heating coil for heating said element, an electrical circuit comprising said coil, a resistance, and means for shunting said resistance, a heat responsive element so disposed as to partake of fluctuations in temperature of the presser element, and connections between said heat responsive element and the shunting means for determining the operation of the latter.

17. A machine for folding collar and cuff blanks comprising a bed plate having a cavity therein, an electrical coil within the cavity for heating the bed plate, a resistance in circuit with the coil, a switch for shunting said resistance, and an electrical circuit comprising a circuit breaker and means for actuating said switch, said circuit breaker being responsive to fluctuations in temperature of the bed plate.

18. A machine for folding collar and cuff blanks comprising a bed plate having a cavity therein, an electrical heating coil for heating the bed plate, a resistance in circuit with the heating coil, a switch for shunting the resistance, an electrical circuit having therein means for actuating the switch, and circuit making and breaking means for said last named electrical circuit comprising contact elements arranged within the cavity in the bed plate, one of said elements being movable toward and from the other under fluctuations in temperature in the bed plate.
